UNITED STATES PATENT OFFICE.

GUSTAF ÖRSTRÖM, OF STOCKHOLM, SWEDEN, ASSIGNOR TO AKTIEBOLAGET GERH. AREHNS MEKANISKA VERKSTAD, OF STOCKHOLM, SWEDEN, A CORPORATION OF SWEDEN.

MACHINE FOR APPLYING DUTY STAMPS, TAX LABELS, OR THE LIKE TO BOXES OR BAGS.

Application filed March 23, 1922. Serial No. 546,184.

To all whom it may concern:

Be it known that I, GUSTAF ÖRSTRÖM, a subject of the King of Sweden, residing at Palsundsgatan 6, Stockholm, Sweden, have 5 invented certain new and useful Improvements in Machines for Applying Duty Stamps, Tax Labels, or the like to Boxes or Bags, of which the following is a specification.

10 This invention relates to a machine for applying duty-stamps, tax-labels or the like to boxes or bags containing cigarettes or other matter. The said stamps, etc., are provided in a magazine and are lifted one by one 15 by a mouth-piece, communicating with an air pump, and are then gripped by a pair of reciprocating tongs which moves the stamp over a device providing the same with paste and then places the same on the box. According 20 to the invention the said tongs are provided on a carrier which, while the tongs drag the stamp over the pasting device and place the same above the box operates on a higher level and is then lowered so that the 25 stamp is dropped in its proper place on the box. In this manner the stamp will not come into contact with the box, until the stamp has been placed above the box and is dropped on the same, and no paste will be 30 swept off from the stamp by the box, which would destroy its appearance. The invention also comprises other arrangements, stated below.

The accompanying drawing shows in a 35 side view a machine arranged in accordance with this invention.

Duty-stamps 1, for instance, are provided in a magazine 2 and acted upon by a vertically movable piston 3 forming the bottom 40 of the magazine. The piston rod 4 is movable in lugs 5 provided on the frame 6 of the machine. To the said rod 4 a wire 7 or the like is fixed passing over guide pulleys 8, 9 and 10 and carrying a weight 11, which 45 thus tends to move the piston 3 and the pile of duty-stamps upwards. The piston is held in its position by a friction arm 12 swingable on a pin 13, the fork-shaped end of the said arm being forced against the piston rod 4 by 50 a spring 12. A mouth-piece 14 is provided on a hollow arm 15, which is carried by and communicates with a tube shaped vertical rod 16, movable but not turnable in lugs 17

on the frame 6. The said rod 16 communicates through a hose 18 with the lower end of a cylinder 19 of an air-pump, the piston 20 of which is raised by a lever arm 21, which is swingable at 22 and provided with a roller 23, bearing against a cam-disc 24 on the driving shaft 25 of the machine. A spring 26 forces the piston 20 downwards. To the rod 16 an arm 27 is fixed, carrying a roller 28 which by a spring 29, fixed to the arm 27 and the lower lug 17, is forced upwards against a cam disc 30 on the driving shaft 25. A presser-foot 32 is fixed to the arm 15 and located preferably near the mouth-piece 14. The said presser-foot extends somewhat below the lower end of the mouth-piece 14.

33 is a horizontal guide carried by a vertical bar 34, which is slidable in a suitable bearing provided in the frame of the machine. The said bar has a roller 35 engaged by lateral projections 36 on a lever arm 37, which is swingably mounted at 22 and provided with a roller 38, bearing against a cam disc 39 on the shaft 25. A slide 40 is provided in the guide 33 and has a roller 41, engaged by lateral projections 42 provided on a lever arm 43, which is fixed to a shaft 44. From the said shaft 44 a second arm 45 projects carrying a roller 46 bearing against a cam disc 47 on the driving shaft 25, the object of which is to move the slide 40 toward the right. A spring, not shown, tends to move the slide 40 toward the left. A pair of tongs is provided on the slide 40, the said tongs comprising a fixed jaw 48 and a swingable spring-actuated jaw 49 provided with an arm 50 which is actuated by a spring 50 fixed to the jaw 49 and adapted to close the tongs. 51 is a roller rotating in a receptacle 52 containing paste, the said roller being driven by a belt 53 and pulleys 54 and 55.

The machine as described operates as follows. The rod 16 together with the arm 15 is lowered by the cam-disc 30, so that the presser-foot 32 is forced against the uppermost stamp in the magazine 2 and forces the pile of stamps and the piston 3 downwards for a short distance, the said operation being rendered possible by the friction arm 12 being brought out of engagement with the piston rod 4 by a pin 56 provided on a disc on the driving shaft 25 and actu-

ating an arm 57 connected with the arm 12. Piston 20 is then raised and creates a vacuum in the cylinder 19 and the mouth-piece 14, so that the latter lifts the uppermost stamp 5 in the magazine 2 by suction. Tongs 48, 49 then grip the said stamp, the tongs being opened and closed by a swingable two-armed lever 58, which is pivoted at 58^x on the guide 33 and by a link 58^{xx} is connected with the 10 lever arm 21. After the said stamp has been gripped, by the tongs 48, 49, the mouth-piece 14 and presser foot 15 are raised followed by the pile of stamps, until the friction arm 12 locks the piston 3, as the pin 56 leaves the arm 57. The slide 40 is moved toward the left by the lever arm 43, so that the tongs drag the stamp over the pasting roller 51 and place the same above the box 59. During the said operations the guide 33 15 is located at such a high level, that the stamp will not touch the box 59 and no paste will be swept off from the stamp by the box. The guide 33 is then lowered, so that the stamp is placed in its proper place on the 20 box, as the tongs are opened by an abutment 60 actuating the arm 50.

Boxes (59) are moved forwards by a piston or the like in a channel 61 leading for instance from a machine filling the boxes 25 with cigarettes. The stamp is firmly pressed on the box by a foot 62 and a brush 63 carried by a bar 64, which is movable in lugs 65 on the frame 6 and raised by a two armed lever 66, pivoted at 67 and actuated by a cam 30 disc 68 on the driving shaft 25. A spring 69 forces downwards the bar 64 together with the presser-foot 62 and the brush 63.

The invention may evidently be modified in some respects without exceeding the limits 40 of the same.

I claim:

1. In a machine for applying duty-stamps, tax-labels, or the like to boxes or bags the combination with a magazine, containing the 45 said stamps, etc., a mouth-piece communicating with an air-pump for lifting the uppermost stamp in the said magazine, means for gripping the said stamp, a pasting device, a reciprocating carrier for the said gripping device, of means for lowering the said carrier, after the gripping means has dragged the stamp over the pasting device and placed the same above the box, etc., so that the stamp is dropped in its proper place on the 50 box without having before touched the same.
2. In a machine for applying duty-stamps, tax-labels or the like to boxes or bags the

combination with a magazine, containing the said stamps, etc., a loose bottom in the said magazine, means actuating the said bottom upwards, a mouth-piece communicating with an air-pump for lifting the uppermost stamp in the said magazine, a presser-foot retaining the stamps while the uppermost stamp is lifted by the said mouth-piece, means for gripping the said stamp, a pasting device, a reciprocating carrier for the said gripping device, means for lowering and raising the said presser foot, of means for holding the said bottom in its position, means for disengaging the said holding means, while the said presser-foot is lowered and raised, and means for lowering the carrier of the gripping means after it has dragged the stamp over the pasting device and placed the same above the box, etc., so that the stamp is dropped in its proper place on the box without having before touched the same.

3. In a machine for applying duty-stamps, tax-labels or the like to boxes or bags the combination with a magazine containing the said stamps, etc., a loose bottom in the said magazine, means actuating the said bottom upwards, a mouth-piece communicating with an air-pump for lifting the uppermost stamp in the said magazine, a presser-foot retaining the stamps, while the uppermost stamp is lifted by the said mouth-piece, means for gripping the said stamp, a pasting device, a reciprocating carrier for the said gripping device, of a tube-shaped vertical rod, carrying the said mouth-piece and presser-foot and effecting communication between the mouth-piece and the air-pump, means for lowering and raising the said rod, means for holding the said bottom in its position, means for disengaging the said holding means, while the said rod together with the mouth-piece and presser-foot is lowered and raised, and means for lowering the carrier of the gripping means, after it has dragged the stamp over the pasting device and placed the same above the box, etc., so that the pasted stamp is dropped in its proper place on the box without having before touched the same.

In testimony whereof I have affixed my signature in presence of two witnesses.

GUSTAF ORSTROM.

Witnesses:

ROBERT APELGREN,
G. SWENSON.
